Specification of Letters Patent.

Patented June 4, 1912.

Application filed March 2, 1911. Serial No. 611,788.

To all whom it may concern:

Be it known that I, WINN E. BROUGHTON, a citizen of the United States, residing in Peabody, county of Essex, and State of Massachusetts, have invented an Improvement in Presses, of which the following description, in connection with the accompanying drawings, is a specification, like letters on the drawings representing like parts.

10 This invention relates to a press especially designed among other uses for marking hides, skins and leather in tanneries, whereby the hides or skins of different qualities or lots may be identified, traced and classified, as they pass through the different processes now commonly practised in tanneries.

20 The invention has for its object to provide a simple, efficient, inexpensive and rapidly working machine for the purpose specified.

Figure 1 is a front elevation of a press embodying this invention, and Fig. 2, a side elevation of the machine shown in Fig. 1 looking toward the right.

25 In the present instance, the invention is embodied in a manually operated machine, in which 10 represents a movable tool or die carrier, which may have secured to or forming part of it a suitable marking device or tool capable of marking hides, skins or leather. The movable carrier 10 is provided with a stem or rod 12, which slides in a guide 13 attached to a supporting upright 14, provided with a bracket or arm 15, 30 for supporting a bed or coöperating lower platen 16.

The tool carrier 10 is moved toward the lower platen 16 by a helical spring 17, encircling a rod 18, extended upwardly from 40 a head 20 on the rod 12. The head 20 is provided with a finger or projection 21 having a notch 22, with which cooperates a locking device herein shown as a finger 23 on a crank or arm 24 fast on a rock-shaft 25 extended through a longitudinal slot or opening 26 in the head 20 and having bearings in the upright 14. The slot or opening 26 in the head 20 permits the tool carrier to be moved downwardly by the spring 17, when 45 the locking finger 23 is disengaged from the notch 22 as will be described.

50 Provision is made for storing up power in the spring 17 before the head 20 is released, so that when released the said head 55 and its attached tool carrier will be moved

substantially in an instant toward the lower platen 16 so as to strike the leather or other work thereon a sharp blow and thereby properly impress upon the work the mark by which it may be identified. In the present instance, the spring 17 bears at its lower end against a collar 27 fixed on the rod 18, and at its upper end against a collar 28 loose on said rod to slide thereon. The loose collar 28 has coöperating with it an arm 29 60 adjustably secured to a rod 30 extended down through a guide 31 and pivotally connected at its lower end to a foot treadle or lever 32 pivoted at 33 to the base 34 of the upright. The rod 30 has also secured to it 65 a disengaging device or knock-off arm 35, which is designed to engage the crank 24 and rock the shaft 25 so as to remove the locking finger 23 from the notch 22 in the head 20, and thus place the latter under the 70 influence of the spring 17.

75 The knock-off arm 35 is adjustably secured to the rod 30 as by the clamping screw 37 so that the rod 30 may be moved a predetermined distance before the locking device 80 23 is disengaged from its coöperating notch 22, which enables the spring 17 to be compressed a given amount so as to store up the power required to move the tool carrier into engagement with the work on the lower 85 platen and strike the work a sharp blow. The downward movement of the rod 30 is effected by depressing the foot treadle 32 and as soon as the work has been marked, the pressure of the foot on the treadle is removed, and the latter is elevated by a spring 90 40 attached to a collar 41 on the rod 30 and to the table 42 which is secured to or forms part of the bracket 15. As the rod 30 is lifted by the spring 40, the spring compressing arm 29 engages a nut 45 on the rod 18 95 and lifts the latter and the head 20, thereby elevating the movable tool carrier into its normal position represented in the drawing. The upward movement of the rod 18 is limited by an overhanging arm 46 erected upon the upper bearing box for the shaft 25 and at or about the time the nut 45 engages the arm 46, the locking device 23 is again engaged with the notch 22 by a spring 47 100 105 which rocks the shaft 25 so as to effect the engagement of the locking device with the said notch.

110 The lower platen may be adjustably mounted in the bracket or arm 15 by means

of the threaded rod 50 and it may be locked in its adjusted position by the nut 51 and set screw 52.

In operation, the leather or other work to be pressed or marked is placed upon the lower platen 16 by the operator, who then depresses the foot treadle to trip the locking device or latch 23 and effect the rapid movement of the tool carrier into contact with the work.

I have herein shown the invention as embodied in a manually operated press or machine, but it is not desired to limit the invention in this respect.

15 Claims:

1. In an apparatus of the character described, in combination, a lower platen, a tool carrier, a slotted head connected with said carrier, a rod extended upwardly from said head, a helical spring encircling said rod, a collar fast on said rod and against which one end of said spring bears, an arm coöoperating with said spring to compress it and store up power, a rod to which said arm is secured, means to move the latter rod, a locking dog coöperating with said slotted head to hold it stationary while the said spring is being compressed, a crank to which said locking dog is attached, a rock-shaft to which said crank is attached, a knock-off arm to engage said crank and rock said shaft to disengage the locking dog from said slotted head, means to elevate the knock-off arm, and means to rotate the said shaft to restore the locking dog into engagement with the slotted head, substantially as described.

2. In an apparatus of the character described, in combination, a lower platen, a tool carrier movable toward and from said lower platen, a spring to move said carrier, a foot treadle, a rod attached to said foot treadle, an arm carried by said rod and co-

operating with said spring, a locking device coöperating with the movable carrier to prevent its movement while the said arm is compressing said spring, and a knock-off arm carried by said rod and coöperating with said locking device to release the said carrier and permit it to be moved by the said spring, substantially as described.

3. In an apparatus of the character described, in combination, a lower platen, a tool carrier, a spring to move said carrier toward the lower platen, a treadle, a rod attached thereto, an arm on said rod engaging the upper end of the said spring to compress the same, means for locking said carrier against movement while said spring is being compressed, and means for releasing said carrier when the spring has been compressed a predetermined amount to permit said spring to move the carrier rapidly toward the lower platen, substantially as described.

4. In an apparatus of the character described, in combination, a lower platen, a tool carrier, a rod connected with the said carrier to move therewith, a spring encircling said rod, a rock shaft, a device fast on the rock shaft and coöperating with the said rod to lock the same against movement by said spring, a compressing arm for said spring, a rod to which the compressing arm is attached, a knock-off device secured to the last-mentioned rod, a crank or arm on said rock-shaft with which the knock-off device coöperates to release the said carrier, and means to rotate said rock-shaft, substantially as described.

In testimony whereof, I have signed my name to this specification in the presence of two subscribing witnesses.

WINN E. BROUGHTON.
